UNITED STATES PATENT OFFICE.

LINN W. SEARLES, OF WASHINGTON, DISTRICT OF COLUMBIA.

SNUBBING DEVICE.

Application filed March 15, 1928. Serial No. 261,864.

My invention relates to improvements in railway crossing gates, and has particular reference to a snubbing device for use in connection with such gates.

5 An important object of the invention is to provide a snubbing device, which is so constructed that it will exert a progressively increasing resistance to the lateral movement of the road arm of the gate, while permitting 10 the same to shift laterally, within limits when struck by an automobile or traveling vehicle.

A further object of the invention is to provide a snubbing device of the above mentioned character, which will automatically return the road arm of the gate to the normal position, after being shifted laterally, and when the load is removed therefrom.

15 A further object of the invention is to provide apparatus of the above mentioned character, embodying an anchor element having a plurality of prongs, so arranged and associated with a support or housing that the anchor element will be automatically adjusted 20 to bring one of the prongs to an uppermost vertical position, when the anchor element is returned to the normal starting position.

25 A further object of the invention is to provide a snubbing device of the above mentioned character, which is automatic and reliable in operation.

30 A further object of the invention is to provide a snubbing device of the above mentioned character embodying an anchor element so constructed that the road arm of the gate, when lowered, may rest upon the anchor element without locking engagement therewith, to permit of the raising of the road arm, such locking engagement automatically occurring 35 when the road arm is shifted laterally.

40 Other objects and advantages of the invention will be apparent during the course of the following description.

In the accompanying drawings, forming a 45 part of this specification, and in which like numerals are employed to designate like parts throughout the same,

50 Figure 1 is a side elevation of a snubbing device embodying my invention, the same being associated with a railway crossing gate,

Figure 2 is a plan view of the same,

55 Figure 3 is an enlarged plan view of the snubbing device,

Figure 4 is a side elevation of the same,

55 Figure 5 is a rear end elevation of the snubbing device,

Figure 6 is a front end elevation of the same,

Figure 7 is a longitudinal vertical section taken on line 7—7 of Figure 3,

Figure 8 is a transverse section taken on line 8—8 of Figure 4,

Figure 9 is a transverse section taken on line 9—9 of Figure 8,

Figure 10 is a similar view taken on line 10—10 of Figure 8,

Figure 11 is a similar view taken on line 11—11 of Figure 8, and,

Figure 12 is a detailed section taken on line 12—12 of Figure 8.

In the drawings, wherein for the purpose of illustration, is shown a preferred embodiment of my invention, the numeral 15 designates the body portion or road arm of a gate, which body portion is capable of swinging both vertically and horizontally. The gate is preferably of the construction shown and described in the co-pending application of Charles H. Gage and Arthur E. Searles, Serial No. 133,152, filed September 2, 1926, 80 for railway gate. The body or road arm portion 15 is formed of an integral or continuous metal rod, bent upon itself between its ends, into a generally U-shaped form. This rod thus bent provides a pair of main 85 side rods 16, connected at their free ends by a loop 17. The rod 15 is preferably formed of piano wire steel.

The numeral 18 designates a vertically swinging support or block, arranged at the 90 opposite end of the body portion 15. This support or block is rigidly mounted upon a horizontal rockshaft 19, journaled in stationary bearings 20. The shaft 19 may be turned by any suitable means, for raising and lowering the gate. Pivoted upon the vertically swinging support 18 is a horizontally swinging block 21, pivoted thereto by means of a pin 22. The rear ends of the rods 16 are anchored or rigidly attached to the block 21. Attached to the block 21, forwardly of the pivot 22, is a shifting pin 27, engaged by leaf-springs 33, attached to a portion of the support 18. These leaf-springs serve to return the body portion 15 of the gate to the normal position, when shifted horizontally therefrom. No further description of the gate, per se, is thought to be necessary.

The snubbing device embodies a housing or frame 35, including sides 36, connected by a 1 top portion 37. This housing or frame may be in the form of a casting. As more clearly

shown in Figures 4 and 8, the numerals 38 and 39 designate bearings, which are substantially identical. These bearings carry flanges 40 and 41. The bearings 38 and 39 are each square in cross section and are substantially identical. These bearings are, therefore, nonrotatable and are held within openings 42, which are also square in cross section, and these openings are formed in the 10 sides 36. The bearings 38 and 39 are held in place by plates 43, attached to the sides 36 by bolts 44.

The numeral 45 designates a stationary non-rotatable shaft, having an intermediate 15 cylindrical portion 46, and end portions 47 and 48, which are square in cross section, and held within the bearings 38 and 39, whereby the shaft can not rotate, and it is also incapable of moving longitudinally perceptibly. The cylindrical intermediate portion 46 has its outer or free end screw-threaded, as shown at 49, and the diameter of the turns of the screw-threads are slightly smaller than the diameter of the 20 unscrew-threaded portion of the cylindrical portion 46. The numeral 50 designates a drum, including a hub 51, which is rotatable upon the cylindrical portion 46, and has its bore smooth and free from screw-threaded 25 engagement with the screw-threads 49. The hub 51, see more particularly Figure 9, is provided in its outer face with a recess 52, which is square in cross section, and receives a traveling nut 53, engaging upon the screw-threads 49. As the hub 51 is rotated, it turns the traveling nut 53, and this traveling nut 30 will shift the hub 51 longitudinally upon the shaft 45.

A friction clutch device is provided for co- 40 action with the drum 50 and the same includes a non-rotatable friction disc 54, having a hub 55, Figure 10, and the bore of this hub is square in cross section, to slidably receive the square end portion 48 of the stationary shaft. The friction disc 54, therefore, can not rotate upon the end portion 48 but may move longitudinally of the same. The friction clutch device embodies a co- 45 acting friction disc 56, which is rotatably mounted upon the exterior cylindrical portion 57 of the hub 55. This friction disc 56, Figure 10, is provided upon its periphery with ratchet teeth 58, adapted to be engaged by a pawl 59, pivoted to the periphery of the drum 50, as shown at 60, and urged toward the disc 56 by a spring 61. The arrangement of the pawl and ratchet teeth is such that when the drum 50 is rotated, to pay out the cable, carried thereby to be described, 55 the friction disc 56 will rotate with the drum, but when the drum is turned in the reverse direction, to rewind the cable, the pawl will trip over the ratchet teeth, and the friction disc 56 will remain stationary. The drum 60 65 50 is provided with an internal annular flange

62, having an annular groove or raceway 63, formed therein, co-acting with the annular groove or raceway 64, formed in the friction disc 54, receiving bearing balls 65. It is thus seen that the friction between the non-rotatable friction disc 54 and the drum 50 is reduced to the minimum, and this will insure the return movement of the drum, to rewind the cable, without liability of the drum sticking or locking.

Resilient means are provided to effect the proper frictional engagement between the friction discs 54 and 56, and this resilient means includes a cylindrical keeper or holder 66, having a hub 67, provided with a bore 68, so Figure 11, which is square in cross section, to receive the outer portion 69 of the hub 55, which outer portion is exteriorly square in cross section. Hence, the keeper or holder 66 may slide longitudinally upon the hub 55, but can not turn thereon. The keeper 66 is provided with recesses 70, receiving compressible coil springs 71, of suitable stiffness, and any suitable number of these springs may be used. These springs project outwardly beyond the inner ends of the recesses 70, and engage a ring 73, the inner edge of which is provided with an opening square in cross section to engage with the portion 69 of the hub 55, which portion is square in cross section. The ring 73 is, therefore, non-rotatable with the carrier 66 and is capable of moving longitudinally upon the hub 55. This ring simply serves as a cap for the springs 71, so that they do not directly engage the friction disc 56. When the friction disc 56 is formed of steel, I would preferably form the ring 73 of copper or bronze for reducing the friction between these parts. A ring nut 74 is arranged within a recess or notch 75, formed in the flange 41, and has screw-threaded engagement with the flange, at 76, and this ring nut bears against the keeper 66, and by suitable rotation of the ring nut, the keeper 66 may be advanced toward the friction disc 56, thereby permanently adjusting the tension of the springs 71.

Mounted within the drum 50 is a torsional coil spring 77 one end of which is anchored to the cylindrical portion 46 of the shaft 115 45, as clearly shown in Figure 12. This attachment is preferably effected by bending the inner end of the spring 77 inwardly for producing a hook 78, which hook engages beneath the lip 79, formed in the shaft. The hook is held in place by a block 80, secured to the shaft by a screw 81. The opposite end of the spring is suitably attached to the periphery of the drum, Figure 7, by bending the same into a hook 82', and securing the same 120 to a lip 83', by a bolt 84'. The arrangement of this spring is such that it is wound up, when the drum is turned to pay out the cable, and will rotate the drum in a reverse direction, 125 when released, to rewind the cable. When the 130

drum 50 is shifted longitudinally, which movement is ordinarily relatively slight, the spring 77 will flex laterally sufficiently, to permit of this operation.

5 The drum 50 has its periphery grooved, as shown at 82, and the cable 83 is wound upon this grooved periphery. One end of the cable is passed through an opening 84, and is clamped to the side of the drum by means of 10 a plate 85. The opposite end of the cable is attached to an anchor element 86.

The anchor element embodies a shank 87, having a bore 88, receiving the end of the cable 83, held in the bore by a lead casting 15 or filling 89, as is well known. The shank 87 is cylindrical. The free end of the shank is tapered at 89. Formed integral with the outer or free end of the shank is a head 90, having three connecting elements or prongs 20 91, arranged in a triangular group, the same being equi-distantly spaced. Each prong 90 has an undercut portion or recess 92 and an inclined face 92'. The shank 87 is adapted to slide within a tubular guide socket 93, the 25 bore of which is cylindrical, to receive the shank. The forward end of the top 37 of the housing is shown at 94, and this portion is curved in a vertical plane, both longitudinally and transversely. As a result of this arrangement, the prong or prongs, when first brought 30 into engagement with the end portion 94 will automatically adjust the anchor element, turning the same upon its longitudinal axis, so that one prong will always be in an upper- 35 most vertical position, when the shank 87 has completed its movement into the guide socket 93. The loop 17 of the body portion or road arm 15 is adapted to engage over and behind the vertically arranged prong 91, being guided 40 toward the same by the inclined surface 92 of the socket 93, if necessary.

The inclined face 92' may also serve to guide the loop 17 to its resting position on the shank 87, if it should descend slightly laterally displaced, due to the flexing of the body 45 portion or road arm 15. When the arm is thus in the lowered position, with the loop 17 resting upon the shank 87, said loop is in alignment with the recess 92, but out of the 50 same. This permits the road arm to be raised, without locking with the prong 91. However, when the arm 15 is shifted laterally, as when struck by a vehicle, the loop 17 enters the recess 92, and the loop is locked to the anchor 55 element.

The snubbing device has its longitudinal axis arranged diagonally with relation to the longitudinal axis of the road arm 15, which will permit the cable to pay out with the 60 minimum lateral friction between the engaging parts.

The operation of the apparatus is as follows:

When the body portion or road arm 15 of 65 the gate is in the closed or lowered position,

the loop 17 is arranged behind the upstanding vertical prong 91. If the body portion 15 of the gate should now be struck by an approaching vehicle, it will swing horizontally in the direction of travel of the vehicle. The 70

lateral pull upon the loop 17 will be transmitted to the cable 83, causing the drum 50 to rotate in the direction to pay out the cable. At the beginning of this paying out rotation, the same is opposed by the friction clutch device embodying the friction discs 54 and 56 and as this paying out rotation continues, the friction clutch device offers a progressively increasing resistance to the paying out rotation of the drum. This increase in resistance is caused by the rotation of the nut 53 by the hub 51, the nut 53 traveling inwardly upon the portion 46 of the stationary shaft 45, shifting the drum 50 in the same direction. This longitudinal shifting of the drum is 80 transmitted to the friction disc 54, through the medium of the bearing balls 65 and associated elements, whereby the friction disc 54 is urged against the friction disc 56, which in turn is urged against the springs 71, whereby 85 the extent of frictional engagement between the frictional discs 54 and 56 is increased. The body portion 15 will thus yield laterally by virtue of the cable paying out action of the drum, and as a progressively increasing 90 resistance is offered to this paying out action, the body portion or road arm 15 will offer a corresponding progressing resistance to the travel of the automobile, until its movement has been completely arrested. When the load 95 is removed from the body portion or road arm 15, the spring 77 will automatically rotate the drum 50 in a reverse direction, the pawl 59, then tripping over the ratchet teeth 58, both friction discs 54 and 56 being then 100 stationary. Upon this return rotation of the drum, the bearing balls 65 produce the least frictional engagement between the drum 50, and the friction disc 54, whereby the spring 105 77 will at all times be capable of returning the drum. Upon the reverse rotation of the drum and its hub 51, the nut 53 will rotate and travel in a reverse direction, thus progressively reducing the extent of frictional 110 engagement between the friction discs 54 and 56. Of course, the body portion or road arm 15 of the gate is raised and lowered by any suitable means, and the loop 17 will readily 115 pass from behind the prong 91, during this operation.

It is to be understood that the form of my invention, herewith shown and described, is to be taken as a preferred example of the same, and that various changes in the shape, size and arrangement of parts may be resorted to without departing from the spirit of my invention, or the scope of the subjoined 125 claims.

Having thus described my invention, I claim:—

1. In a snubbing device, a rotatable member, a flexible element carried thereby, a friction clutch device having connection with the rotatable member in a manner to oppose its rotation in a direction to pay out the flexible element and to render the member free to rotate in an opposite direction without being opposed by said friction clutch device, and means to progressively regulate the action of the friction clutch device including a traveling nut rotated by said rotatable member. 5 70
2. In a snubbing device, a shaft, a rotatable member mounted upon the shaft, a flexible element carried by the rotatable member, a clutch device, pawl and ratchet means connecting the clutch device with the rotatable member so that the clutch device will oppose the rotation of said member in a direction to pay out the flexible element, means for exerting increasing pressure upon the friction clutch device including a traveling nut having screw-threaded engagement upon the shaft, and rotated by the rotatable member. 15 75
3. In a snubbing device, a shaft, means for supporting the shaft and holding the same against rotation, a drum rotatable upon the shaft, a flexible element carried by the drum, a spring arranged within the drum and attached to the shaft and to the drum, a friction clutch device carried by the shaft and including a rotatable friction clutch disc and a non-rotatable friction clutch disc, pawl and ratchet means connecting the rotatable friction clutch disc with the drum, means for applying increasing pressure to the friction clutch device including a traveling nut having screw-threaded engagement with said shaft, and rotated by the drum. 30 80
4. In a snubbing device, a shaft, means for supporting the shaft and holding the same against rotation, a drum rotatable upon the shaft, a flexible element carried by the drum, a spring arranged within the drum and attached to the shaft and drum, a friction clutch device carried by the shaft and including a rotatable friction clutch disc and a non-rotatable friction clutch disc, anti-friction means arranged between parts of the drum and the non-rotatable friction clutch disc, pawl and ratchet means connecting the rotatable friction clutch disc and drum, and means for applying increasing pressure to the friction clutch device including a traveling nut having screw-threaded engagement with the shaft and rotated by the drum. 45 85
5. In a snubbing device, a shaft, means for supporting the shaft and holding the same against rotation, a drum rotatable upon the shaft, a spring within the drum and connected with the shaft and drum, a flexible element carried by the drum, a friction clutch device mounted upon the shaft and including a non-rotatable friction clutch disc and a rotatable friction clutch disc, said drum and friction clutch disc being shiftable longitudinally of the shaft, pawl and ratchet means connecting the rotatable friction clutch disc and drum, resilient means engaging the friction clutch device and adapted to apply increasing pressure to the same when the friction clutch device is shifted longitudinally of the shaft toward the same, means whereby the friction clutch device is shifted longitudinally by the longitudinal movement of the drum, and a traveling nut having screw-threaded engagement with the shaft and driven by the drum and serving to shift the drum longitudinally of the shaft in one direction. 10 90
6. In a snubbing device, a shaft having an intermediate cylindrical portion and end portions which are polygonal in cross section, a support receiving said end portions to hold the shaft against rotation, a drum having a hub rotatable upon the intermediate cylindrical portion of the shaft, said hub having a polygonal opening and the hub being shiftable longitudinally of said shaft, a traveling nut having screw-threaded engagement with the shaft and arranged within the recess so that the nut is turned by the shaft and effects the longitudinal movement of the drum in one direction, a spring arranged within the drum and connected with the shaft and with the drum, a flexible element carried by the drum, a nonrotatable friction clutch disc having a hub provided with a bore which is polygonal in cross section to receive the adjacent end portion of the shaft, the last named hub having a cylindrical portion and a portion which is polygonal in cross section, a rotatable friction clutch disc mounted upon the last named cylindrical hub portion and engaging the non-rotatable friction clutch disc, pawl and ratchet means connecting the rotatable friction clutch disc and the drum, the hub of the non-rotatable friction clutch disc being shiftable longitudinally of the shaft, a carrier mounted upon the last named polygonal hub portion, springs mounted upon the carrier and exerting pressure upon the friction clutch discs, and a non-rotatable ring interposed between the springs and the friction clutch device and having a part engaging the last named polygonal hub portion. 15 95
7. The combination with a crossing gate including a movable road arm provided at its end with a loop, of a snubbing device for co-action with said arm, including a support positioned near the path of travel of the free end of the arm, an anchor element guided in its movement upon said support and embodying a shank and a prong providing a recess at its rear, the arrangement being such that when the arm is lowered the loop will rest upon the shank in substantial alinement with the recess and out of the recess so that the arm is free to be raised, the loop entering the recess when the arm is shifted laterally whereby the loop is locked to the prong, and the 10 100
- 105 110 115 120 125 130

flexible element connected with the anchor, and paying out means mounted upon the support and connected with the flexible element.

- 5 8. In a snubbing device, a support provided near its top with a generally horizontal guide socket, said support having its face forwardly of the guide socket inclined vertically in longitudinal and transverse sec-
10 tions, an anchor element embodying a shank to enter the guide socket and three prongs carried by the shank and arranged in a triangular group, said prongs being adapted to engage with the inclined faces of the sup-
15 port when the shank is moved toward and into the guide socket whereby one of the prongs automatically assumes an upper vertical position, a flexible element secured to the shank, and winding means carried by the sup-
20 port and connected with the flexible element.

9. The combination with a railway crossing gate embodying an arm capable of swinging vertically and horizontally, of a snubbing device for co-action therewith, including a
25 support, an attaching element mounted upon the support and movable with relation thereto and adapted for detachable engagement with the free end portion of the arm, a rotatable member mounted upon the support, a flexible element wound upon the rotatable member and connected with the attaching element, and means to offer increasing resistance to the rotation of the rotatable member in a direction to pay out the flexible element.

30 10. The combination with a railway crossing gate embodying an arm capable of swinging vertically and horizontally, of a snubbing device for co-action therewith, including a support, an attaching element mounted upon the support and movable with relation thereto and adapted for detachable engagement with the free end portion of the arm, a rotatable member mounted upon the support, a flexible element wound upon the rotatable member and connected with the attaching element, means to offer increasing resistance to the rotation of the rotatable member in a direction to pay out the flexible element, and means to rotate the rotatable member in a reverse direction to wind the flexible element thereon.

11. The combination with a railway crossing gate embodying an arm capable of swinging vertically and horizontally, of a snubbing device for co-action therewith, including a support, an attaching element mounted upon the support and movable with relation thereto and adapted for detachable engagement with the free end portion of the arm, a rotatable member mounted upon the support, a flexible element wound upon the rotatable member and connected with the attaching element, a friction clutch device, and pawl and ratchet means connecting the friction clutch device with the rotatable member.

12. The combination with a railway crossing gate embodying an arm capable of swinging vertically and horizontally, of a snubbing device for co-action therewith, includ-
70 ing a support, an attaching element mounted upon the support and movable with relation thereto and adapted for detachable en-
gagement with the free end portion of the arm, a rotatable member mounted upon the support, a flexible element wound upon the 75 rotatable member and connected with the at-
taching element, a friction clutch device, pawl and ratchet means connecting the friction clutch device with the rotatable member, and means to rotate the rotatable member 80 in one direction with relation to the friction clutch device.

13. The combination with a railway crossing gate embodying an arm capable of swinging vertically and horizontally, of a snub-
85 bing device embodying an attaching ele-
ment, means whereby the arm is locked to the attaching element when shifted hori-
zontally and the arm being free from con-
nection with the attaching element to move 90 upwardly when it is in the normal transverse position, a rotatable drum carried by the sup-
port, a flexible element wound upon the drum and connected with the attaching element and 95 means to oppose the rotation of the drum in a direction to pay out the flexible element.

14. The combination with a railway crossing gate, embodying an arm capable of swinging vertically and horizontally, said 100 arm having a loop near its free end, of a snubbing device arranged for co-action with the loop of said arm, said snubbing device including a support, an attaching element having an upstanding part to enter the loop, 105 the arrangement being such that the upstand-
ing part is free from locking engagement with the loop when inserted therein and the arm is in the normal transverse position, whereby said arm may be raised, said loop 110 having locking engagement with the upstand-
ing part when the arm is shifted horizontally with the upstanding part within said loop, a flexible element connected with the attaching element and winding means con-
nected with the flexible element and adapted 115 to offer a resistance to the paying out of the flexible element.

15. The combination with a railway crossing gate embodying an arm adapted to swing 120 vertically and horizontally, of a snubbing de-
vice for co-action with the arm, said snub-
bing device embodying a support, an attach-
ing element carried by the support and 125 movable with relation thereto, means where-
by the attaching element may have detach-
able locking engagement with the arm, and
friction clutch means to oppose the movement
of the attaching element.

16. The combination with a railway cross- 130

ing gate embodying an arm adapted to swing vertically and horizontally, of a snubbing device for co-action therewith comprising a support having a socket, of an attaching element movable into and out of the socket, means whereby the attaching element may have detachable locking engagement with the arm, and means to oppose the movement of the attaching element out of the socket.

10. 17. The combination with a railway crossing gate embodying an arm adapted to swing horizontally, of a snubbing device for co-action therewith including a support having a socket, an attaching element movable longitudinally within the socket, means for effecting a detachable engagement between the attaching element and arm, a flexible element secured to the attaching element, and means to oppose the paying out of the flexible element.

18. In a snubbing device, a rotatable member, a flexible element carried by the rotatable member, a friction clutch device, pawl and ratchet means connecting the friction clutch device with the rotatable member so that the friction clutch device will oppose the rotation of said member in a direction to pay out the flexible element, means for exerting increasing pressure upon the friction clutch device including a traveling nut rotated by said rotatable member, and a spring to turn the rotatable member in a direction to wind the flexible element thereon.

19. The combination with a railway crossing gate embodying a road arm capable of swinging vertically and horizontally, of a snubbing device for co-action therewith, including a support, an attaching element mounted upon the support and movable with relation thereto, and adapted for detachable interlocking engagement with the road arm, a flexible element connected with the attaching element, and means to control the paying out movement of the flexible element by offer-

ing resistance to such paying out movement. 45

20. The combination with a railway crossing gate embodying a road arm capable of swinging vertically and horizontally, of a snubbing device for co-action therewith, including a support, an attaching element mounted upon the support and movable generally in the direction of the traffic approaching the road arm and adapted for detachable interlocking engagement with the road arm, a flexible element connected with the attaching element, and means to control the paying out movement of the flexible element by offering resistance to such paying out movement. 50 55

21. The combination with a railway crossing gate embodying a road arm capable of swinging vertically and horizontally, a snubbing device for co-action therewith, including a support, an attaching element mounted upon the support and movable with relation thereto, and adapted for detachable interlocking engagement with the road arm, a flexible element connected with the attaching element, a movable member engaging the flexible element for controlling its paying out 70 to the movement of said member in one direction.

22. The combination with a railway crossing gate embodying a road arm capable of swinging vertically and horizontally, a snubbing device for co-action therewith, including a support, an attaching element mounted upon the support and movable generally in the direction of traffic approaching the road arm and adapted for detachable interlocking engagement with the road arm, and means to control the movement of the attaching element in one direction by offering resistance to such movement. 75 80 85

In testimony whereof I affix my signature.

LINN W. SEARLES.
